UNITED STATES PATENT OFFICE.

NIELS LANG, OF CLEVELAND, OHIO.

DESIGN FOR A REFLECTOR.

Application filed February 12, 1925. Serial No. 12,352. Term of patent 7 years.

To all whom it may concern:

Be it known that I, NIELS LANG, a citizen of the Dominion of Canada, residing at Cleveland, in the county of Cuyahoga and State of Ohio, have invented a new, original, and ornamental Design for Reflectors, of which the following is a specification, reference being had to the accompanying drawing, forming a part thereof.

Figure 1 is a perspective view of a reflector, showing my new invention.

Figure 2 is a top plan view of the same.

What I claim is:

The ornamental design for a reflector substantially as shown.

NIELS LANG.
